NO. 13,816

UNITED STATES PATENT OFFICE.

CHARLES F. RITCHEL, OF BRIDGEPORT, CONNECTICUT, ASSIGNOR TO THE UNEXCELLED FIREWORKS COMPANY, OF NEW YORK, N. Y.

DESIGN FOR A TOY PISTOL.

SPECIFICATION forming part of Design No. 13,816, dated March 27, 1883.

Application filed January 26, 1883. Term of patent 3½ years.

To all whom it may concern:

Be it known that I, CHARLES F. RITCHEL, a citizen of the United States, residing at Bridgeport, in the county of Fairfield and State of Connecticut, have invented and produced a new and original Design for Toy Pistols, of which the following is a specification.

My newly-invented design for a toy pistol for exploding caps consists of the cap-holder and the hammer for exploding the cap, designed in the form of colored boys, and mounted on the barrel of the pistol in the attitude of a "butting match," together with the words "Butting Match," figured on the sides of the barrel, to be used together or separately.

The accompanying engraving represents my new design for toy pistols in side elevation.

The cap-holder a consists of the figure of a colored boy resting on the barrel by his hands and knees, with his head toward the breech, the top of the cap of the figure being the holder for the paper cap to be exploded. The hammer b, for exploding the cap, is designed in the figure of another colored boy resting upon his hands and knees at the breech of the pistol, with his head toward the other figure, and being on the movable piece, which is thrust forward by the spring when the trigger is pulled to explode the cap. Both figures are arranged with their feet projecting beyond their respective ends of the barrel; but this is not essential, and may be modified, if desired.

The words "Butting Match" are figured on the sides of the barrel, as represented in the accompanying print, but may be figured or arranged in any approved modification thereof.

I do not limit myself to the particular features of the design of the figures, as they may be modified in the details; but

I claim—

1. The design for a toy pistol, consisting of the cap-holder and the cap-exploding figure in the characters and attitude of boys engaged in a butting match.

2. The design for a toy pistol, consisting of the cap-holder and the cap-exploder figured in the characters and attitudes of boys engaged in a butting match, together with the words "Butting Match," figured on the sides of the pistol.

In witness whereof I have hereunto signed my name in the presence of two subscribing witnesses.

CHARLES FRANCIS RITCHEL.
